Primary Examiner — Derrick E Holland*Assistant Examiner* — Jennifer O King(74) *Attorney, Agent, or Firm* — Jack Schwartz & Associates, PLLC(57) **CLAIM**

The ornamental design for a utility sleeve, as shown and described.

DESCRIPTION

FIG. 1 is a top view of the utility sleeve of the present invention;

FIG. 2 is a bottom view thereof;

FIG. 3 is a right side view thereof;

FIG. 4 is left side view thereof;

FIG. 5 is a front side view thereof;

FIG. 6 is a back side view thereof; and,

FIG. 7 is a top perspective view thereof in a closed state. The broken lines shown represent stitching and form no part of the claimed design.
